Primary Examiner — Manpreet Matharu*Assistant Examiner* — Rebecca Tsehay(74) *Attorney, Agent, or Firm* — NSIP Law(57) **CLAIM**

We claim the ornamental design for a drum-type washing machine, as shown and described.

DESCRIPTION

FIG. 1 is a front perspective view of a drum-type washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a cross-sectional view taken through line 8-8 of FIG. 4.

The broken lines in the figures show portions of the drum-type washing machine which form no part of the claimed design. The dot-dash broken lines define boundaries of the claimed design and form no part of the claimed design.
